UNITED STATES PATENT OFFICE.

JOHN L. OSGOOD, OF BUFFALO, NEW YORK.

TOOL-HANDLE.

1,074,891.

Specification of Letters Patent.

Patented Oct. 7, 1913.

Application filed January 19, 1912. Serial No. 672,155.

To all whom it may concern:

Be it known that I, JOHN L. Osgood, a citizen of the United States, residing at Buffalo, in the county of Erie and State of 5 New York, have invented a new and useful Improvement in Tool-Handles, of which the following is a specification.

This invention relates more particularly to improvements in wooden tool handles of 10 the sort used for files and other hand tools having a tapering tang which is driven into an axial hole in the end of the handle for securing the handle on the tool. Since the handle is held on the tool by friction only, 15 it works loose from time to time in the use of the tool and the tang has to be driven farther and farther into the handle to properly secure the tool, with the ultimate result that a great many handles are split and 20 destroyed unless they are specially reinforced. Patent No. 857,894, granted to me June 25, 1907, discloses a handle of this kind having a metal tube reinforcement extending into it from the tool-attaching end 25 around the tang hole for preventing the handle from splitting. This construction has been found by extended use over a considerable period of time to make the handles 30 practically indestructible. However, the strengthening tube must be comparatively thin and in order, therefore, to secure the strength necessary to withstand the excessive outward strain resulting from the expansion 35 of the wood caused by driving in the wedge shaped tangs, the reinforcing tubes have to be seamless, drawn from high grade stock, or they must be turned down to the proper thickness from heavier tubes. The tubes 40 are, therefore, expensive to produce and add materially to the cost of the handles.

The object of this invention is to provide an improved reinforcement for preventing the splitting of the handles which affords the advantages of the tubes employed in said 45 patented handle, but which makes the handles stronger and more durable and, at the same time, is less expensive than said tubes. This is accomplished by inserting into the body of the handle between the surface 50 thereof and the tang hole, in place of the metal tube before employed, a reinforcement consisting of one or more coils of fine, strong wire. Since the wire has great tensile strength in the direction in which it is wound, or circumferentially, the wooden core 55 within the coils and into which the tang of

the tool is driven is surrounded by a reinforcement or binder which has ample strength to resist the expansion of the inclosed core of wood when the tang is driven 60 into it. A reinforcement composed of coiled wire is stronger than a tube of corresponding thickness, because the grain of the metal runs lengthwise in the tube instead of circumferentially thereof, as in the wire coil. 65 Then too, the walls of a tube are substantially rigid and cannot give or yield under the outward pressure, and if the strain is too great, it will split the tube. But, as the convolutions of the wire coils are relatively 70 movable, one portion of the coil is adapted to yield slightly relative to another portion under the expansion of the inclosed wooden core, so that it is practically impossible in any ordinary use of the handles to break the 75 wire coil and split the handle.

In the accompanying drawings: Figure 1 is a side elevation and Fig. 2 is a longitudinal section of a tool handle embodying the invention. Fig. 3 is a fragmentary view 80 thereof showing the strengthening coil in elevation. Fig. 4 is a cross section thereof in line 4—4, Fig. 2, and Fig. 5 is an end elevation thereof. Fig. 6 is a longitudinal section of a slightly modified construction. 85

Like reference characters refer to like parts in the several figures.

Referring first to the handle shown in Figs. 1 to 5. A represents the handle which may be of any shape suitable for the handles 90 of files and other hand tools having a tang adapted to be driven into the handle for securing the handle thereon. Wooden handles are usually demanded for hand tools, and the handle is, therefore, preferably made of 95 wood, but it could be made of other material. An axial hole *a* is provided in the inner end of the handle to receive the tang of the tool and this end of the handle is preferably reduced to form the usual neck *b* which is surrounded and protected by the usual ferrule *c*. The neck is, however, preferably made shorter than usual and the ferrule is driven into the adjacent shoulder of the handle, as shown in Fig. 2, to prevent it from coming 100 off, if the wood shrinks.

D represents the coiled wire reinforcement which extends lengthwise into the body of the inner or tool-attaching end portion of the handle around the tang hole *a* and preferably between the same and the circumference 110 of the neck *b*. The reinforcement extends

well into the handle and is preferably composed of two or more wire coils. The handle is provided in any suitable manner with a narrow annular recess into which the coils 5 are forced and in which they are tightly held in place with spaces d between the adjacent coils. These spaces allow the inclosed core of wood to expand slightly between the coils under the outward pressure caused 10 by driving the tang into the handle, and permit the tang to be driven well into the handle and firmly seated, but the coils prevent the tang from splitting the handle. The coils preferably extend into the handle to or 15 beyond the point to which the tang or the tool extends when it is driven into the handle to the limit, so that the tang can not possibly expand and cleave the handle beyond the coils.

20 The flanged outer end of the ferrule c covers and hides the outer end of the coil recess and prevents the possibility of the outer end of the coil from protruding from the recess.

25 In the handle shown in Fig. 6, the reinforcement consists of a single continuous wire coil D' , instead of the several shorter coils, as in the construction first described. This figure also shows a similar reinforcing 30 coil E inserted into the other, or outer, end of the handle for preventing the splitting thereof. This coil can be used or not as preferred, and a similar coil can be used in the outer end of the handle shown in 35 Figs. 1-5, if desired.

The handle provided with the described reinforcing device has all of the advantages and desirable features of the ordinary ferrule-tipped wooden handles. It has 40 the same long wooden grip or hand-hold extending from end to end of the handle, except for the portion covered by the ferrule; the wooden socket into which the tang of the tool is driven and retained; and it 45 may have the same appearance. In addition to these usual requirements, the handle is rendered practically indestructible by the coiled wire reinforcement or binder. The wire coil reinforcement or binder de-

scribed in addition to being stronger and 50 less expensive than the strengthening tube referred to, has the further advantage that it permits a slight expansion of the inclosed wooden core when the tang is driven into it, so that the core is not compressed so hard 55 as when a non-yielding tube is used. Consequently the tang can be driven into the handle more readily and the core retains some of its elasticity and therefore more firmly grips and holds the tang.

60

I claim as my invention:

1. A wooden tool handle having a hole in one end to receive the tang of a tool, said handle having a narrow annular recess formed therein around said hole and 65 between the walls of the same and the outer surface of the handle, and a coiled wire reinforcement in said recess, said reinforcement extending at least approximately from end to end of said hole, substantially as described.

2. A wooden tool handle having a hole in one end to receive the tang of a tool, said handle having a narrow annular recess formed therein around said hole and between the walls of the same and the outer surface of the handle, and a plurality of reinforcing members inserted in said recess each of which comprises a helical coil of wire, said coils being separated by intervening spaces, substantially as described.

3. A wooden tool handle having a hole in one end to receive the tang of a tool, said handle having a narrow annular recess formed therein around said hole and between the walls of the same and the outer surface of the handle, a coiled wire reinforcement in said recess, and a ferrule on the end portion of the handle, said ferrule extending over and closing the end 80 of said recess, substantially as described.

Witness my hand, this 17th day of January, 1912.

JOHN L. OSGOOD.
